(57) **CLAIM**

The ornamental design for a safety protector for tumor puncture, as shown and described.

DESCRIPTION

FIG. 1 is a perspective view showing my new design for a safety protector for tumor puncture;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view showing the safety protector for tumor puncture in a closed position.

The broken line showing represents portions of the article not claimed and forms no part of the claimed design.
